UNITED STATES PATENT OFFICE.

MURDOCH MACDONALD, OF CLEVELAND, OHIO, ASSIGNOR TO THE MACDONALD TICKET AND TICKET BOX COMPANY, A CORPORATION OF OHIO.

HOLDER FOR TICKETS, CHECKS, &c.

No. 856,410.

Specification of Letters Patent.

Patented June 11, 1907.

Application filed March 27, 1905. Renewed April 10, 1906. Serial No. 310,966.

To all whom it may concern:

Be it known that I, MURDOCH MACDONALD, a citizen of the United States, residing at Cleveland, in the county of Cuyahoga and State of Ohio, have invented certain new and useful Improvements in Holders for Tickets, Checks, &c.; and I do declare that the following is a full, clear, and exact description of the invention, which will enable others skilled in the art to which it appertains to make and use the same.

The present invention relates to holders for tickets, checks or similar articles, suitable for use on railways of various kinds, in restaurants, stores, places of amusement, etc., where it is desired to give to the passenger, purchaser or spectator, a ticket, check or voucher of suitable character in exchange for value received, at the same time retaining a corresponding portion or stub which may afterward be turned over to the auditor or other accountant. In a device of this kind it is of the greatest importance that the user shall be able to quickly and accurately make the necessary indications on the receipt or portion handed to the passenger, purchaser or spectator and simultaneously therewith make a corresponding auditor's portion, stub or voucher. The importance of this will be readily appreciated when it is considered that the holder has its greatest use on railway train and bus systems where the ability to collect fares with great rapidity and accuracy, as in rush hours, is the first consideration. It is also of great importance to provide a holder of such character that the auditor's stub or voucher will be concealed from view once the passenger's or purchaser's portion of the ticket or check is removed, thus furnishing an accurate check on the user and dispensing with all book-keeping or accounting on his or her part. By reason of this the user will have more time to attend to other duties.

The object of the invention is to provide a holder which will fulfil the exacting requirements set forth above, and at the same time be simple and rugged in construction, cheap to manufacture, and not liable to get out of order either by use or misuse.

In the accompanying drawing, which illustrates one of the embodiments of my invention, Figure 1 is a plan view of the holder

showing a pad comprising a number of tickets or checks in position; Fig. 2 is a perspective view of the holder with the ticket or check pad and the retaining device removed; Fig. 3 is a perspective view of the pad-retaining device; Fig. 4 is a cross-sectional view of the holder, with the pad in place, showing the position of the auditor's stubs therein; Fig. 5 is a cross-sectional view of the casing with the pad and holding device removed; and Fig. 6 is a perspective view of a pad suitable for use in the holder.

C represents the casing of the holder, comprising a base portion, a curved back and top and two end portions, and D a removable pad-retaining plate. The plate is provided with a lip d on its right-hand side, which is adapted to be slipped under the inturned edge c on the casing. Rising vertically from said lip for a short distance is a portion d' that conceals the right-hand side of the stub of the pad from view. Formed integral with, or secured to said portion and extending parallel with the base of the holder, is the flat portion of the plate which engages the pad and confines the same within the holder, with the exposed and concealed portions lying in planes making an angle to each other. The retaining plate is locked in position by the pin 2, the lower end of which is adapted to pass through the base of the casing and enter a lock affixed to the under side thereof. The key for the lock is retained by the auditor or other duly authorized person so that once the pad is locked in place, the user does not have access thereto and hence cannot see what the stubs indicate. The curved portion of the casing terminates in a relatively thin edge 3. On the under side of the pad-retaining plate are one, two or more devices for holding the pad in proper alinement. In the present embodiment of the invention two pins 6 are provided for the purpose that extend through orifices 5, Fig. 6, in the pad.

The pad P is composed of a plurality of counterpart sheets of comparatively thin paper and is held against the severing edge by the plate D. The sheets are suitably fastened together to form a pad of convenient size and shape and one that can be readily handled. As shown in cross-section the exposed and stub portions of the pad form, in the present embodiment of the invention, an

acute angle to each other, and the individual sheets are placed under an initial spring tension due to the flexing or bending of the sheets. The angle made by the portions of the pad can be varied to suit the conditions of service. The tension on the sheets thus arranged is sufficient to cause the stub portion of each severed sheet to spring away from the severing edge 3. I regard this as a very important feature of the invention since it greatly facilitates the rapidity with which the user can issue tickets or checks.

I believe it to be broadly new with me to provide a holder for tickets, checks, etc., wherein the sheets composing the pad are placed under initial stress with the idea of causing the stub portions thereof to spring away from the severing edge when released.

In service all the user has to do is to make the proper indications on the individual sheets before they are severed, and the stubs will take care of themselves. When the spring tension on the pad is sufficient the stubs will disappear from view one after the other as tickets or checks are severed. When the tension on the pad, due to the character of the paper used, is small, or to the fact that the pad has been in the holder for some time and the paper has taken a "set," the stub portion of each sheet may be released from frictional contact with the severing edge 3, either by depressing the exposed end of the pad slightly or by moving it bodily inward by a slight amount. This action will permit the stubs to spring back one after the other as shown in Fig. 4 and be concealed from view.

In event of the spring tension of the paper being insufficient to hold the successive sheets in proper engagement with the severing edge 3, a spring means, such as the wing E or its equivalent is provided. In the present illustration of the invention the said means is hinged to the inner end of the plate D and normally pressed upward by one or more small springs coiled around the longitudinally extending pin of the hinge.

The character of the yielding means for forcing the successive sheets of the pad against the severing edge can obviously be changed without departing from the spirit of my invention.

It sometimes happens that it is desirable to support the pad within the casing at a point above the base. To accomplish this a plate G is provided that is brazed or otherwise secured to the upright portion d' of the pad-retaining plate, the said plate being perforated to receive the ends of the pins 6 and 60 support the same.

In order to make the proper indications on both the exposed and concealed portions of each sheet, one, two, three or more cutters or perforations are provided. In the present instance three cutters 7, 8 and 9 are provided.

These are mounted to slide individually and longitudinally of the guide 10, the latter being supported by the ends of the holder and also by resting on the curved top portion thereof. The cutters are provided with sharpened ends that lie in the plane of the exposed portion of the pad, and are provided with surfaces that grip the overhanging edges of the guide 10. In order to prevent them from moving too freely each cutter is or may be provided with a small spring 12 of suitable construction.

The sheets composing the pad are duplicates, and each is printed with the necessary data arranged in parallel columns. For example, for railway, train and bus systems, columns of figures are provided indicating the fares to be charged for different distances traveled over. Columns containing the names of streets, stations or localities are also provided, together with any other necessary data. The severing or tearing line of the sheets is located midway between the columns.

Assuming the holder to be loaded and ready for service the mode of operation is as follows: The user takes the holder in the left hand and, with a thumb or finger, moves a cutter along the guide 10 until it coincides in position with the amount of fare to be collected. A second cutter is moved along the guide until it registers with the place where the journey began; the third cutter is moved along the guide until it registers with the place where the journey is to cease. The user then takes the top sheet between the thumb and finger of the right hand and swings it in an arc about the severing edge 3 as an axis. This causes the cutters to cut V-shaped slots in the sheet, and by a movement of the hand toward the body the sheet is severed. The detached portion with the three V-shaped notches is then handed to the passenger for a receipt. By practice the users of these holders are able to sever the exposed portions of the sheets by a practically continuous movement of the hand, thus insuring rapid collection of fares and issuing of receipts. If the tension on the sheets of the pad is sufficient the stub of the severed sheet will of its own accord spring away from the severing edge; if not, the pad is either slightly depressed or moved inward by a slight amount or both, after which the position of the pad is restored. The stub portion of the ticket will correspond to the severed portion as to the fare paid, the distance traveled over, etc., but instead of having V-shaped notches it will have V-shaped projections of the same size as the notches. When the tickets or checks have been used wholly or in large part the holder is turned over to the auditor and reloaded by unlocking the bolt and removing the pad, reinserting a new one and re-mounting the plate D and inserting the

bolt 2. By examining the projections on the stub portions of the tickets or checks turned in the auditor can readily ascertain the sum of money to be accounted for.

5 The specific construction of the ticket holder is not claimed herein as it forms the subject matter of my application for patent, S. N. 293,854, filed December 29, 1905.

In accordance with the provisions of the 10 patent statutes, I have described the principle of operation of my invention, together with the apparatus which I now consider to represent the best embodiment thereof; but I desire to have it understood that the apparatus shown is only illustrative, and that the 15 invention can be carried out by other means.

What I claim as new and desire to secure by Letters Patent of the United States,

1. In a device of the character described, 20 the combination of a casing arranged to receive a pad composed of flexible sheets, one portion being within the casing, the other exposed, a severing edge, and a means which retains the pad within the casing and places 25 all of the sheets under initial stress so that the stubs of the severed sheets have a tendency at all times to retreat from the severing edge:

2. In a device of the character described, 30 the combination of a casing having an opening and arranged to receive a pad composed of flexible sheets, the stub portion of the pad being within the casing and the portion to be severed extending through the opening, a 35 severing edge against which the sheets are pressed one after the other as the portions outside of the casing are severed, and a holder which retains the stub portion within the casing, bends the pad to put the sheets 40 under initial stress and holds the surface of the sheets in engagement with the severing edge, the holder, severing edge and pad being so constructed and arranged that a bodily movement of the pad after a sheet is 45 severed frees the stub portion of the sheet from said severing edge and causes it to disappear from view.

3. In a device of the character described, 50 the combination of a casing arranged to receive a pad composed of flexible sheets, concealing one portion and exposing the remainder, a severing edge, one or more cutters adjustable with respect to said edge, and a means for retaining the pad within the casing, the said means being so constructed and arranged that it tends at all times to withdraw the stubs of the sheets from the severing edge and from view.

4. In a device of the character described, 60 the combination of a casing having an opening and arranged to receive a pad composed of flexible sheets, concealing one portion and exposing the other through the opening, a severing edge against which the sheets are 65 pressed one after the other as the exposed

portions are severed, a removable holder which forms one wall of the casing, holds the sheets in a bent position against the severing edge and thus places them individually under initial stress to cause them to spring 70 away from said edge, and means for attaching the pad to the holder to facilitate its insertion and removal from the casing.

5. In a device of the character described, 75 the combination of a casing, arranged to receive a pad composed of flexible material, concealing one portion and exposing the other, means for holding the pad in a bent position within the casing so that the sheets are placed under individual stress, to cause 80 them to move away from the severing edge when released, one or more devices for making indications or records on the successive sheets, and a severing edge arranged to successively engage the sheets and retain the 85 stub portion against the severing edge until released by a relative movement of the main body of the pad and said severing edge.

6. In a device of the character described, 90 a casing having a back portion rounded transversely and provided with a severing edge along the front and top thereof and a series of cutters slidably engaged on the top of said casing and provided with points extending beyond said severing edge at an angle there- 95 to, in combination with a pad-confining plate removably attached over the front and top of said case, means confining the sheets of said pad in the casing connected with said plate, and a spring-pressed wing on one edge 100 of said plate to hold the tickets to the severing edge.

7. A device of the character described consisting of a casing having its front edge constructed to form a severing edge for the 105 sheets and open across its front beneath said edge, in combination with a plate removably secured over said front, a spring-pressed wing having its edge opposite said severing edge, and indenting cutters slidably mounted along 110 said severing edge projecting outward at an angle to said edge.

8. A device of the character described, 115 comprising a casing with a rounded back portion and a severing edge along its front and top, a series of pointers slidably mounted on the top of said casing and having points in line with said severing edge, in combination with a retaining mechanism for a pad comprising a plate removably locked in the top 120 of said casing, and a spring-pressed wing engaged on the edge of said plate and adapted to press the pad against the said severing edge.

9. A device of the character described 125 comprising a sheet-metal casing with a severing edge at its top front, in combination with a pad-retaining mechanism consisting of a plate adapted to overlap a portion of the pad, means to lock said plate in the said casing, 130

means to engage the pad and prevent its being drawn out, and means to hold the pad up against said severing edge.

10. A device of the character described, comprising a severing edge for the pad sheets along its front and top, and open at its front to insert the pad, in combination with means to confine said pad comprising a plate constructed along its front edge to be locked upon said casing, a spring-pressed wing hinged on the inner edge of said plate, and cutters slidably mounted on the said casing and having points bent to an inclination and operatively related to said severing edge.

15. In a device of the character described, a casing adapted to hold a pad and to conceal the auditor's stub when the exposed portion has been removed, said casing having an opening lengthwise across its front bordered by a severing edge for the pad sheets, a yielding plate to hold the pad against said severing edge, and means to fix the pad in the casing, comprising a support on which the pad rests, and means holding the pad upon said support, the said casing having a rounded back behind said severing edge to conceal the sheets of the pad after the tickets have been detached.

20. In a device of the character described, 25 a case adapted to receive a pad composed of flexible sheets having a rounded back and top portion terminating at its front in a severing edge for the sheets, said severing edge

being on a plane below the highest point in the top of the case, whereby when the exposed portion of a sheet is torn off of the stub it has room to spring back and be concealed within the upper portion of the case, in combination with means to confine the pad comprising a plate removably secured over the front of said case and extending inward at its rear to a plane substantially beneath the highest point in the top of the case, whereby when the pad is confined beneath said plate the angle of bend for the pad is made acute to facilitate the springing of the stubs back into the case.

30. In a device of the character described, a casing to hold a pad and to conceal the auditor's stub when the ticket proper has been severed, said casing having an opening lengthwise across its front bordered by a severing edge for the ticket, a yielding plate to hold the pad against said severing edge, and means to fix the pad in the casing comprising a support on which the pad rests, and means holding the pad upon said support, the said casing having a rounded back behind said severing edge to conceal the sheets of the pad after the tickets have been detached.

35. In testimony whereof I sign this specification in the presence of two witnesses.
